[57] CLAIM

The ornamental design for a truck hoist cylinder mount, as shown and described.

DESCRIPTION

FIG. 1 is a top perspective view of a truck hoist cylinder mount according to my new design, here showing the cylinder mount connected to a truck frame indicated in broken lines and not forming a part of the design;

FIG. 2 is a bottom perspective view thereof;

FIG. 3 is a side elevational view thereof;

FIG. 4 is a top plan view thereof;

FIG. 5 is a bottom view thereof;

FIG. 6 is a front elevational view thereof; and,

FIG. 7 is a rear elevational view thereof.
